METHOD FOR BURNING LIQUID FUELS

Homer A. Tiffany, Glen Rock, N. J.

Original application April 17, 1929, Serial No.
355,688. Divided and this application March
11, 1935, Serial No. 10,544

5 Claims. (Cl. 158—117.5)

The present invention relates to methods for burning liquid fuels such as oil, and particularly to a method of liquid fuel combustion to be carried out in a furnace having a boiler wall or the like to be effectively heated.

5 The present application is a division of my copending application Serial No. 355,688, filed April 17, 1929, which discloses fuel burning apparatus of the type in which a fire box is closed at the bottom by a hearth above which projects a motor-driven head for projecting fuel and air. More particularly, said copending application discloses and claims an improved type of such apparatus, in which the hearth and head are designed and operated so that a remote or peripheral flame wall functions as the real burner at which combustion is initiated; the head being specially designed and operated so as to prevent the fuel and air from igniting until impact with said flame wall, a characteristic of this type of head and hearth being that the flame thus initiated at the wall may be as diffused, and combustion as perfect, as may be desired.

10 The present invention concerns an improved method of combustion adapted for use in many furnaces, but primarily perfected for use in connection with hearths and ignition walls of the general type disclosed in the Heath Patents No. 1,886,675, granted November 8, 1932, and No. 1,979,465, granted November 6, 1934. Both show and describe the preferred fuel and air projector that I use for practicing my improved method, while specifically acknowledging me as the inventor of the novel features thereof.

15 In burning oil in accordance with this new method, the rotary head is driven at relatively constant low speed, say 1700 to 1750 R. P. M. regardless of the amount of fuel that is being burned; combustion is prevented until impact, and is made certain of initiation upon impact with dependence upon the relations as well as the proportions of oil, air, and burned out products of combustion in the projected draft; and the objects of my invention include producing a 20 projection method under which the oil, air, and products of combustion are projected in more perfect relation for insuring the desired results, under widely-varying conditions of fire box sizes and the amount or range of oil feed. Important 25 features of my invention, each of which are novel and all of which cooperate to produce the desired results include the following:

20 The oil is projected outwardly in a plurality of individual streams. Preferably the streams are few in number to afford wide spaces between

them, thereby facilitating the downward and radial movement of the hot burned out products of combustion so that the latter are mixed with and substantially envelop the streams of oil spray. Preferably the streams are provided through rotating spouts the outlets of which are radially distant from the rotational axis substantially as far or farther than the periphery of the rotating head and, preferably also, farther than the tips of the fan blades which are employed to establish the outward draft of a thin layer of air between the upper surface of the hearth and the oil spray. Preferably the spouts project above the level of the top surface of the head or are otherwise associated therewith so that there are spaces between them facilitating inflow of hot products of combustion, and so that their projecting surfaces function to a noticeable extent as fans tending to centrifugally project said products of combustion.

25 Among other features of specific contributory importance which may be employed in a preferred head for practicing the invention is that of having the peripheral orifices for the projected oil arranged so that when the head is rotated, the leading edge of each orifice projects farther from the axis than does its trailing edge.

30 Preferably, a radial draft of air is discharged beneath the oil streams across the upper surface of the hearth. In practice, the slope of the hearth, the speed of rotation of the head and the distance between the head and the flame wall are so proportioned that the hearth surface parallels the oil trajectory nearly enough to prevent substantial amounts of oil from impact, air- 35 mixing and burning except on and adjacent the flame wall. It may be desirable to have the upper surface of the hearth slope downwardly from the central head to the peripheral flame wall so as to more closely parallel the falling 40 trajectory of the oil for a greater distance.

35 In the preferred form of apparatus for carrying out my mechanical method, the head receives air from below the hearth, the supply being preferably regulated by a valve controlling the air 45 intake opening. The low pressure condition produced in the head is the resultant of stack draft and the centrifugal effects of the fan and of the spouts upon the air in each. The centrifugal effects of the head cause a considerable amount 50 of hot burned out gases, mainly nitrogen and carbon dioxide, to be admixed with air and fuel layers projected from the head and thus assist in preventing combustion before the layers reach the flame wall. The hot burned out gas is fur- 55

ther effective to maintain the head at the proper temperature and to lessen the skin tension and prevent over-sized oil globules or particles from being projected from the spouts. The decrease in skin tension will obviously further cause the globules to follow the desired, definite path of projection. The burned out gas, being rich in carbon dioxide has the further well known effect of diluting the air draft, prolonging and diffusing the combustion and, consequently, promoting complete combustion at the flame wall.

The invention may be more fully understood from the following description in connection with the accompanying drawing, wherein:

15 Figure 1 is a fragmentary vertical sectional view through the hearth of a boiler showing a preferred form of projector head in an operative position for carrying out the method of the present invention;

20 Figure 2 is an enlarged top plan view of the same head with parts broken away and in section for the sake of clarity;

Figure 3 is a transverse sectional view on the irregular line 3—3 of Figure 2;

25 Figure 4 is a side elevational or edge view of the head; and

Figure 5 is a sectional detail showing the manner in which steel wool packing may be arranged in the spouts.

30 The method of this invention can best be explained by first describing the above mentioned apparatus, as follows:

The hearth 10 is generally similar to the hearth disclosed in the prior Heath patents above identified, including a peripheral upstanding flame wall 11 in the region of the water leg 12 of the boiler. This hearth slopes downwardly from the central opening which accommodates the projector head to the flame wall.

40 The hearth may be supported on plate 13, the edges of which rest on ledge ring 14 and the intermediate portion of which is sustained by the outwardly turned flange 15a of hollow, generally frusto-conical air collar 16, the latter being supported in any suitable way, of which there are several now well known. Member 16 preferably forms a liner for the central opening in the hearth, being provided at its upper edge with an inwardly and downwardly turned flange 18.

50 The oil projector head preferably comprises a sand casting including a generally cylindrical body portion 20, the top 21 of which is closed over save for central opening 22. The lower edge of the body is formed with an inwardly projecting annular flange 23 terminating in upturned lip 24, the lip, flange and body wall forming a relatively shallow annular trough 25 into which the oil to be projected is delivered. Externally the body 20 is formed with an upwardly inclined 55 external flange 26 which divides the body into an upper oil projector portion and a lower fan portion.

60 The fan includes a plurality of blades 27 below and integral with the flange 26 and the oil projector portion includes a plurality of spouts or conduits 28 integral with and above the flange for discharging individual streams of oil.

65 These projectors are of generally tapering formation, their inner ends being of general rectangular shape, as best seen in Figure 3, and their outer ports or orifice being substantially circular. The projectors preferably inclined slightly upwardly, this inclination being generally in the plane of the flange 26. It will be noted that 70 they also project above the flange so that their

exterior surfaces function somewhat as fan blades to accelerate recirculation of the hot burned out gases and to project them outwardly with the oil and air. The trailing edges or sides of the projectors are disposed approximately radially of the head and the leading edges of the projectors are disposed approximately tangentially of the body 20 and project somewhat farther beyond the periphery of the flange than do the trailing edges, tending in this manner to create a slight suction at the outlet ports or orifices of the projector. The important result of having the trailing walls of the projectors disposed in a general radial plane is that the oil should be positively centrifugally flung or impelled from the orifices of the projector spouts and not be permitted to simply leak out of them, as might be the case were the trailing edges disposed at the same radial distance from the axis of the head as the leading edges.

20 In the drawing I have shown a four-stream projector, but a six-stream projector may be used if necessary, and the four or six stream devices readily converted into two or three stream devices by the simple expedient of plugging certain 25 of the spouts.

The head is mounted within the central opening of the hearth defined by the air collar 16 with the lower outer edges of the fan blades just clearing the inner upper edge of the collar. The air 30 draft upwardly through the collar 16 is controlled by a vertical adjustable damper collar 30 which may be raised from the position of Figure 1 to restrict the size of the annular air inlet opening as desired.

35 The head is mounted upon the upper end of a vertical shaft 31 driven from any suitable power source such as an electric motor as is now common in this art. Oil supply pipe 32 extending upwardly into the head carries a laterally extending oil 40 spout 33 which overhangs the trough 25 and delivers oil into the trough.

45 The overhang of the spout 33 presents a slight problem in assembling the head which is taken care of by the provision of an opening 22, of considerably larger diameter than the motor shaft 31 and of slightly smaller diameter than the fixed driving collar 34 of the motor shaft, a pin 34a to fit the opening 34b (see Fig. 2) in the head and a nut 35 which coacts with the collar to clamp 50 the head in position. The upper end of the motor shaft is threaded at 36 for the reception of the collar and nut. This oversize opening 22 permits the head to be dropped down over the threaded end of the motor shaft, moved laterally until the 55 trough is clear of the spout 33 and then brought back to center and clamped by screwing home the nut 35.

60 The sand casting of the head affords a very material advantage in operation under some conditions. The minute protuberances on the rough internal surfaces of the casting are wetted by the oil, thereby increasing the area of contact of the oil with the heated metal surface. Another effect is to retard and distribute the oil film more uniformly, this being of advantage in rendering the resulting spray more uniform, particularly when relatively large amounts of oil are being discharged. This, however is not always essential.

65 In operation, when the head is set in motion 70 and the oil feed turned on, the oil collecting in the bottom of the trough 25 will form, under the action of centrifugal force, a film which gradually creeps up the interior of the wall 20 and as it reaches the spouts flows outwardly through them, 75

and is centrifugally thrown with considerable force and in a fairly straight trajectory toward the flame wall 11, this oil, when the motor is running at its normal speed, tending to impinge upon the flame wall without deposition on the hearth at points between the projector and the wall.

The air draft on the other hand is projected radially from the fan blades 27, the air trajectory being below the oil trajectory so that there is only partial admixture of the oil and air except in the immediate neighborhood of the flame wall.

For most efficient operation the air supply is adjusted by raising the collar 30 until a substantially blue ring of flame is initiated at and in the region where oil and air are mixed by impingement on the peripheral ignition wall. In order to simplify illustration I have not shown any ignition means arranged near the periphery of the hearth.

The head being rotated clockwise, the blades 27 constitute a large volume fan drawing air through the variable passage B, (Fig. 5), between the stationary collar 16 and the upwardly adjustable collar 30. In normal operation this passage is sufficiently restricted to tend to create a vacuum in the interior space A. The four nozzles 28 constitute another fan tending to create suction within in the head, and, through annular passage D, this suction tends to take effect in the same space that the fan blades 27 draw from. Thus, the many blades 27 and the four nozzles 28 constitute two fans connected in parallel to the same source. When the main air supply is unrestricted there may be a small amount of air delivered through nozzles 28, but this amount is much smaller than that delivered through blades 27, because the flow section through passage D and the four little nozzles is very much less than that of the annulus through which blades 27 discharge.

It will be seen that by adjusting collar 30 to appreciably restrict the air inlet to the chamber A, the fan blades 27 may actually recirculate some of the hot combustion gases by drawing them through the nozzles 28 in opposite direction to the flow of outgoing oil. This recirculation, however, can do no harm and under certain conditions it is of advantage to have combustion gases mixed with the primary air to produce a low blue flame of very high efficiency.

In operation, oil is supplied to the trough 25 through the interior nozzle 33. Centrifugal force causes a film of this oil from trough 25 to creep up the walls and ultimately to be thrown off as a spray projected from the rear lips of the four nozzles 28. Centrifugal force may also cause a relatively small volume of air to be projected through the nozzles 28 as above explained, while a much larger volume of air is being projected by the fan blades 27. The nozzles 28 project substantially above the plane of the top plate 21 of the rotor. Consequently said plate, together with the upwardly projecting surfaces of the nozzles, constitute in effect another fan whereby hot products of combustion are projected in the same horizontal plane with the oil spray. Thus the composite draft produced by the nozzles consists of a non-combustible mixture of hot products of combustion, oil spray, and possibly a small percentage of air. When this composite mixture strikes the periphery of the hearth, the oil spray is further atomized, and mixed with the air from the fan blades. This final mixture easily ignites at starting, and when the apparatus is in full operation so that the refractory impact surfaces are at high temperature, substantially perfect com-

bustion begins and is maintained entirely at the periphery.

The factors which control the blueness or efficiency of the flame ring which impinges almost directly on the cold water leg of the boiler are of course the correct admixture of air and oil which is determined to a large extent by the extent of volatilization and atomization of the oil when the latter reaches the combustion wall. By proper metering of the air and the oil this mixture will be substantially the same at the periphery of a 17" hearth or of a 56" hearth, since while the additional oil flow necessary for the larger hearth results in the oil being projected from the head in larger particles, the added distance through which the oil must travel and in which it is subjected to the heat of the fire box increases volatilization to such an extent that there is no appreciable difference in the efficiency of the mixture.

It is not only possible but desirable in certain instances to promote a substantial atomization of oil in or at the head, and this may be readily accomplished by the introduction of small wads of steel wool such as 35x shown in Figure 5 in the oil nozzles. These steel wool wads are rather loosely packed and the wool is of fairly coarse grade, the wads being held against flying out centrifugally by the pins 36x.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:—

1. A method of effecting combustion of liquid fuel, said method consisting in flinging a fuel spray in non-combustible form in a general radial direction toward an outward zone of combustion, simultaneously directing a supply of air along a path closely paralleling that of said fuel spray but without substantial admixture with the latter, simultaneously directing a quantity of gases of combustion along the path of said fuel spray to assist in preventing the air stream from commingling with the fuel spray to form a combustible mixture, and merging the air stream and the fuel spray for combustion in the region of said outward zone.

2. The method of effecting combustion in a chamber having a surface to be heated, which comprises impinging individual liquid fuel streams against said surface; passing a stream of air in the general direction of the fuel streams toward said surface in sufficient quantity to support combustion of the fuel streams; mixing said air and fuel streams substantially solely closely adjacent the locus of fuel impingement on said surface; and burning the mixture at said surface.

3. In a method of liquid fuel combustion the steps of projecting from a liquid fuel source a plurality of separate non-combustible sprays including liquid fuel toward a surface that is relatively remote from said fuel source and separated therefrom by an intermediate zone of non-combustible spray travel; and simultaneously directing a flow of air along a path closely paralleling said non-combustible sprays but without sub-

stantial admixture with the latter in the intermediate zone so that air is mixed with the spray substantially solely in the region of said surface and where combustion takes place.

5. A method of effecting liquid fuel combustion consisting of the steps of projecting liquid fuel spray in multiple jets substantially horizontally through space and entirely without interference toward a relatively remote upright surface, without sufficient air for combustion and with sufficient velocity to carry said jets into impingement with said surface; and supplying air for combustion under forced draft into intersection with the projected jets only in the zone 10 of impingement to thus form a combustible mixture; and burning said combustible mixture in said zone.
15. 5. In a method of liquid fuel combustion, the

steps of flinging from a liquid fuel source a plurality of separate non-combustible sprays including liquid fuel toward a surface that is relatively remote from said fuel source and separated therefrom by an intermediate zone of non-combustible spray travel; and simultaneously directing a flow of air along a path closely paralleling said non-combustible sprays but without substantial admixture with the latter in the intermediate zone so that air is mixed with the spray substantially solely in the region of said surface and where combustion takes place; and simultaneously directing a quantity of gases of combustion along the paths of said fuel sprays to assist in preventing the directed air from commingling 15 with the fuel sprays to form a combustible mixture prior to reaching said surface.

HOMER A. TIFFANY.
